Primary Examiner — Lauren R Calve(74) *Attorney, Agent, or Firm* — Laubscher, Spendlove & Laubscher, P.C.(57) **CLAIM**

The ornamental design for a baby food container, as shown and described.

DESCRIPTION

FIG. 1 is a front perspective view of a baby food container according to our invention;

FIG. 2 is a top plan view thereof;

FIG. 3 is a front elevation view thereof;

FIG. 4 is a bottom plan view thereof;

FIG. 5 is a rear elevation view thereof;

FIG. 6 is a left side elevation view thereof;

FIG. 7 is a right side elevation view thereof; and,

FIG. 8 is a front perspective view thereof shown in an open condition.

The broken lines shown represent unclaimed subject matter and form no part of the claimed design.
